UNITED STATES PATENT OFFICE.

CHARLES M. LUNGRÉN, OF NEW YORK, N. Y., ASSIGNOR, BY MESNE ASSIGNMENTS, TO THE SIEMENS LUNGRÉN COMPANY.

REGENERATIVE GAS-BURNER.

SPECIFICATION forming part of Letters Patent No. 351,386, dated October 26, 1886.

Application filed June 26, 1884. Serial No. 136,052. (No model.)

To all whom it may concern:

Be it known that I, CHARLES M. LUNGRÉN, a citizen of the United States, and a resident of New York, in the county of New York and State of New York, have invented certain new and useful Improvements in Gas-Burners, of which the following is a specification.

My invention relates to regenerative gas-burners, and more especially to a form described in another application for patent heretofore filed by me, and patented June 24, 1884, No. 300,879, and consisting of an inverted gas-burner, a flame plate or surface over which the flame is directed, and an upwardly-extending flue for the escape of the products of combustion.

My invention consists in certain combinations of parts and peculiarities of construction designed to produce better combustion and to give greater luminosity to the flame, which combinations and constructions will be herein described in connection with the accompanying drawings, and will be then specified in the claims.

In the accompanying drawings, Figure 1 is a vertical central section of a burner containing the improvements herein claimed. Figs. 2, 3, 4 are vertical sections of burners, showing modified ways of carrying out the invention. Fig. 5 is a cross-section through the gas-burner tubes. Fig. 6 is a horizontal cross-section illustrating the arrangement of the air ducts or passages conveying air to the root of the flame.

G, Fig. 1, indicates a gas-tube by which the burner is supported, and which conveys gas to the gas-burner. At the lower end of said tube is a gas-chamber closed at the bottom by a suitable plate, G', while from said chamber extend downwardly a series of tubes, g g, (shown in cross-section, Fig. 5,) which are open at their lower ends, and are properly arranged to project a flame over a flame plate or director, D, of preferably porcelain or other refractory material.

Instead of a series of tubes, the burner may consist of an annular chamber having openings either in the lower edge or in its outer wall near the bottom, as shown in my previous application. The plate D may be of any

desired form or shape, and I do not limit myself in this respect. It may be supported by its lower edge, as shown, or by the top, and it may be a separate piece, as shown, or be formed by contracting the lower end of the air-shell A'. A button or deflecting-surface, B, of any suitable kind, placed below the flame and suspended by a rod, R, serves to deflect air outwardly against the flame and the flame outward and over the plate D. Air is delivered to the root of the flame and on one or both sides thereof through the chamber or tube in which the tubes g are contained. The passage for the egress of the flame and air is made sufficiently contracted to cause the air-current to come into direct and full contact with the flame at its root.

A A' indicate two shells or chambers, one within the other, and connected by a series of radiating passages, a a, as indicated in Fig. 6. The outer shell, A, is provided with a downward extension, C, for causing the flames and products of combustion to sweep inward away from the globe C, which latter is hung from and closes the mouth of the tube A. The tube A supports the chimney F, through which the products of combustion and heated air escape after circulating around the cross-tubes a a, and heating the air conveyed through the latter to the chamber formed by the tube A', and through the latter to the root of the flame.

A" indicates an outer shell or hood depending from the shell A, and surrounding the outer ends of the tubes a a.

S indicates a reflector hung from A". Air is brought to the tubes a a through the hood A".

In order to do away with the tendency to redness or want of luminosity in the body and tip of the flame which may exist when the burner is constructed as thus far described, so that the passages at the root of the flame are arranged to cause the air to strike the flame fully, I provide an additional air-supply for the body and tip of the flame through the bottom or top of the globe by the devices to be now described.

H indicates a tube, which extends through an opening in the bottom of the globe, and is hung from the rod R by any suitable means, or is otherwise supported. Its upper end opens

beneath the deflecting-plate B, and between its flaring mouth and the under surface of the plate B air is delivered to the body of the flame. The additional air thus supplied is 5 heated in its passage to the flame through the chamber or conduit, one wall or surface of which is formed by said deflecting-plate. The bottom of the tube H is partially closed by a button upon the rod R, which button may be 10 screwed up and down to adjust the amount of the additional air-supply thus provided.

In the modification shown in Fig. 2 the additional air is supplied between the edges of an opening in the bottom of the globe and the 15 edges of a glass-plate, K, closing said opening. The edges of the plate or of the opening, or both, are made irregular or provided with suitable crimps, corrugations, grooves, or slots, to permit air to enter in limited or regulated 20 quantity. What heat is imparted to the additional air-supply thus provided comes from contact with the sides of the globe.

In Figure 3 the additional air-supply is admitted at the top of the globe, and is heated by 25 the shell C, through which latter the heated products of combustion pass. The globe is hung from a perforated ring, E', suitably attached to or supported by the shell A, and the air enters through said perforations. The 30 shade S is in this instance hung from the same ring, so as to assist in collecting and delivering the air through said openings, and to also prevent back-draft or tendency of the flames to escape through said openings. For this 35 purpose the shade preferably extends below the level of the flame. Instead of being a shade, the part S might be of glass or other translucent material.

In the modification of my invention shown 40 in Fig. 4 the additional air supplied to the body of the flame is not only heated by the escaping products of combustion, but also by contact with the under side of the deflecting plate or body, as in Fig. 1. In this instance 45 the deflector B is formed at the bottom of a tube or shell, B', contained within the burner and connected at its top with the chamber formed by shell A', so that a portion of the air entering through the tubes a a, and heated 50 by the escaping products of combustion, may pass through the tube B' and be delivered to the body and tips of the flame. The tube or shell B' is hung from the rod R, or supported in any other suitable manner in the position 55 shown. In the drawings it is shown as supported by a nut, b, which is provided with radiating arms attached to the interior of the tube B', and is adjustable on the rod so as to vary the position of the deflecting plate or 60 surface B, formed upon or attached to its lower end.

If desired, the gas-burner may be made without any air-passage through it, and the whole of the air to supply the under surface of the 65 flame may be admitted through the base of the globe, or part of it through the base and a portion through the top.

I do not limit myself to any particular form of gas tip or burner, nor to any particular shape or configuration of flame plate or surface over which the flames are made to sweep. The construction and arrangement may be varied in other ways without departing from the spirit of my invention, and the arrangement shown in the various figures of drawings may 70 be used in various combinations for the same 75 burner.

I am aware of the English Patents No. 3,742, July 31, 1883, and No. 4,109, August 28, 1882, and I make no claim to the constructions shown 80 therein.

What I claim as my invention is--

1. The combination of an inverted annular gas-burner, an air-chamber surrounding the burner and provided with vertical walls, said chamber having an inlet for air at its upper end and an outlet for air at its lower end, an escape-flue surrounding the air-chamber and provided with vertical walls, a flame-director formed by an outward and upward continuation of the outer wall of the air-chamber, terminating in line with the vertical wall of the escape-flue, leaving a horizontal passage for the flames and products of combustion between the end of said flame-director and the end of said escape-flue, and an inclosing-globe, substantially as and for the purpose described. 90

2. The combination of an inverted annular gas-burner, an air-chamber surrounding the burner and provided with vertical walls, said chamber being connected with the outer air at its upper end by passages which lead across the escape-flue, and provided with an outlet for air at its lower end, an escape-flue surrounding the air-chamber and provided with 100 vertical walls, a flame-director formed by an outward and upward continuation of the outer wall of the air-chamber, terminating in line with the vertical wall of the escape-flue, leaving a horizontal passage for the flames and products of combustion between the end of 105 said flame-director and the end of said escape-flue, and an inclosing-globe, substantially as and for the purpose described.

3. The combination of an inverted annular gas-burner, an air-chamber surrounding the burner and provided with vertical walls, said chamber having an inlet for air at its upper end and an outlet for air at its lower end, an escape-flue surrounding the air-chamber and provided with vertical walls, a flame-director formed by an outward and upward continuation of the outer wall of the air-chamber, terminating in line with the vertical wall of the escape-flue, leaving a horizontal passage for the flames and products of combustion between the end of said flame-director and the end of 115 said escape-flue, an inclosing-globe, and air-inlets arranged between the outer edges of the globe and the escape-flue, substantially as and 120 for the purpose described. 125

4. The combination of an inverted annular gas-burner having downwardly-directed orifices for the emission of gas at its lower end

and a deflecting-button beneath its lower end, an air-chamber surrounding the burner, said chamber having an outlet for air at its lower end and connected at its upper end to an air-conduit leading to it from the outer air across the escape-flue, an escape-flue, the lower end of which surrounds the upper part of the air-chamber, an inclosing-globe, and air-inlets arranged between the outer edge of the globe and the escape-flue, substantially as specified.

5. The combination of an inverted annular gas-burner having downwardly-directed orifices for the emission of gas at its lower end, an air-chamber surrounding the burner, said chamber having attached to its lower end a flame-director springing from its extreme lower end and formed integral with the sides thereof, said chamber being connected at its upper end to an air-conduit leading to it from the outer air across the escape-flue, an escape-flue, the lower end of which surrounds the upper part of the air-chamber, an inclosing-globe,

10

15

20

and air-inlets arranged between the outer edge of the globe and the escape-flue, substantially as specified.

6. The combination of an inverted annular gas-burner composed of a ring of tubes open at their lower ends for the emission of gas, an air-chamber surrounding the burner, said chamber having an outlet for air at its lower end and being connected at its upper end to an air-conduit leading to it from the outer air across the escape-flue, the lower end of which surrounds the upper part of the air-chamber, an inclosing-globe, and air-inlets arranged between the outer edge of the globe and the escape-flue, substantially as specified.

Signed at New York, in the county of New York and State of New York, this 23d day of June, A D. 1884.

CHARLES M. LUNGREN.
